UNITED STATES PATENT OFFICE.

CHARLES L. DURBORAW, OF BALTIMORE, MARYLAND, ASSIGNOR TO
MEYER METZGER, OF BALTIMORE, MARYLAND.

GRIP FOR SHOE-POLISHING CLOTHS.

No. 820,630.

Specification of Letters Patent.

Patented May 15, 1906.

Application filed September 12, 1903. Renewed October 13, 1905. Serial No. 282,593.

To all whom it may concern:

Be it known that I, CHARLES L. DURBORAW, a citizen of the United States, residing at Baltimore, in the State of Maryland, have invented certain new and useful Improvements in Grips for Shoe-Polishing Cloths, of which the following is a specification.

This invention relates to improvements in grips for shoe-polishing cloths.

10 The object of the invention is to provide a cheap, simple, and efficient device which can readily be attached to or detached from the ends of a cloth used for polishing shoes and which will afford means whereby the said cloth can be firmly held in the hand without cramping the fingers of the user.

Other features of the invention will be fully set forth in the following specification and pointed out in the claims.

20 In the accompanying drawings, Figure 1 is a perspective view of my improved grip attached to the end of a piece of cloth. Fig. 2 is an end view. Fig. 3 is a cross-section on the line X X of Fig. 1, the cloth being omitted. Fig. 4 is a bottom plan view. Fig. 5 is a perspective view of one of the T-shaped fastenings.

Similar reference-numerals designate like parts throughout the several views of the drawings.

30 Referring to the accompanying drawings, forming part of this specification, 1 designates the lower section, and 2 the upper section, of the grip. The lower section 1 is provided 35 with a central concavity 3, running the entire length of the said section, and an approximately V-shaped groove 4 4 on each side of and running parallel with the said concavity.

3. Each end of the section 1 is provided 40 with a slot 5 5, into each of which is pivoted an approximately T-shaped fastening 6 6. The said fastening is pivoted to the section 1 by means of a pin 7 7, passing through the aperture 8 in the lower end of the said fastening and into the sides of the said section, as indicated by dotted lines in Figs. 2 and 4.

45 The upper section 2 is provided on one surface with a central convexity 9, extending the entire length of the said section and 50 adapted to fit into the concavity 3, and an approximately V-shaped projection 10 10 on each side of said convexity 9, adapted to fit into the grooves 4 4. The ends of the section 2 are slightly rounded at 11 and are each pro-

vided with a slot 12 12, into which the shank 55 of the T-shaped fastening 6 projects when the sections are locked together. The rounded ends 11 permit the head of the fastenings 6 6 to ride up over the upper surface of the upper section 2.

60 When it is desired to secure the grip to the end of a cloth, the fastenings 6 6 are slipped out of the slots in the section 2 and hang pendent to section 1. The sections 1 and 2 are then separated, the cloth placed therebetween, and said sections again placed together. The fastenings 6 6 are then forced up over the rounded ends 11 of section 2 until the heads thereof rest upon the upper surface of said sections, as shown in Fig. 1, whereby the 70 cloth will be securely held by said sections 1 and 2.

Having thus described my invention, what I claim is—

1. As an article of manufacture, a grip comprising two sections, and two approximately T-shaped fastenings pivoted to one section and adapted to fit over the other section, as and for the purpose described.

2. As an article of manufacture, a grip comprising two sections each having a slot in each end thereof, and means fitted in the slots of one section and adapted to operate in the slots of the other section to lock the said sections together.

3. As an article of manufacture, a grip comprising two sections each having a slot in each end thereof, and an approximately T-shaped fastening pivoted in each slot of one section and adapted to take into the slots of the other section to lock the said sections together.

4. As an article of manufacture, a grip comprising two sections, one of said sections having a concavity extending the entire length thereof and an approximately V-shaped groove on each side of, and running parallel with, the said concavity, and the other section having a convexity extending the entire length thereof and an approximately V-shaped projection on each side of and running parallel with the said concavity, and means for locking the said sections together.

5. As an article of manufacture, a grip comprising two sections, one of said sections having a concavity extending the entire length thereof and an approximately V-shaped groove on each side of, and running parallel

with, the said concavity, and the other section having a convexity extending the entire length thereof and an approximately **V**-shaped projection on each side of and running parallel with the said convexity, each of said sections having a slot in each end thereof, and means pivoted in the slots of one section and adapted to be forced into the slots of the other section to lock the said sections together.

6. As an article of manufacture, a grip comprising two sections, one of which is provided with a concavity extending the entire length thereof and an approximately **V**-shaped groove on each side of and running parallel with said concavity, and a slot in each end

thereof, and the other section having a convexity extending the entire length thereof and an approximately **V**-shaped projection on each side of and running parallel with said convexity, and a slot in each end thereof, and an approximately **T**-shaped fastening pivoted in each slot of one section and adapted to be forced over the other section, to lock the sections together. 25

In testimony whereof I affix my signature in the presence of two witnesses.

CHARLES L. DURBORA^W.
